UNITED STATES PATENT OFFICE.

EMIL HÄNISCH AND MAX SCHROEDER, OF HAMBORN, PRUSSIA, GERMANY.

PROCESS OF OBTAINING SULPHUR FROM FURNACE-GASES.

SPECIFICATION forming part of Letters Patent No. 361,761, dated April 26, 1887.

Application filed June 10, 1885. Serial No. 168,287. (No specimens.) Patented in Germany January 25, 1885, No. 33,100; in France May 18, 1885, No. 156,381; in England May 26, 1885, No. 6,404; in Belgium May 30, 1885, No. 68,914; in Spain June 24, 1885, No. 7,743, and in Norway September 29, 1885.

To all whom it may concern:

Be it known that we, EMIL HÄNISCH and MAX SCHROEDER, subjects of the King of Prussia, residing at the village of Hamborn, in the 5 Kingdom of Prussia, German Empire, have invented a new and useful Improved Process of Obtaining Sulphur, of which the following is a specification.

Our invention relates to a process of obtaining sulphur from furnace calcination or roasting gases in which sulphurous acid is present; and it consists in bringing the sulphurous acid in the gaseous mixtures not direct to reduction, but only after it has been separated from 15 the other injurious or neutral components accompanying it, this being effected by maintaining the same at a glowing heat within a closed space after it has been passed through or over a glowing bed of fuel.

20 The process is carried out as follows: We separate the sulphurous acid from the other gases accompanying it by causing the furnace or calcination or roasting gases to flow upward in a tower against a downward flow therein of cold water in the form of rain. The water absorbs the sulphurous acid, but not the gases mixed therewith, (nitrogen, oxygen, carbonic acid.) The watery SO_2 solutions (anhydrous sulphurous-acid solutions) are heated in a series 25 of closed lead pans, by steam or otherwise, to boiling heat, and in this manner we obtain sulphurous acid in the form of gas. The water-vapor taken up and carried along in this portion of the process is separated from the evolved 30 gas by means of a worm or coil of pipe. We then reduce the sulphurous acid, for which purpose we employ the apparatus shown in the accompanying drawing, in which the figure is a vertical longitudinal section of the apparatus.

35 40 We conduct the sulphurous acid through the pipe *a* into the cylinder *b*, which is charged with coal, coke, or charcoal fuel, and is heated to a glowing heat. The sulphurous acid, which has been half reduced in the cylinder *b*, but is 45 mixed with sulphur-vapors and carbon oxides, &c., is caused to pass to the cylinder *e* through the connecting-pipe *d*. The cylinder *e* is filled with fire-bricks or other suitable fire-proof material. It is impinged upon and heated by 50 the hot gases coming from the cylinder *b*

through the apertures *f*. We now conduct the as yet unreduced acid through the glowing mass of fire-brick in the cylinder *e* in a downward direction. By this latter means we operate the transformation of the second half of 55 the sulphurous acid in conjunction with the formation of sulphur-vapor and carbonic acid. We conduct these gases out of the cylinder *e* into the preliminary condensing-chamber *g*, and thence to the main condensing-chamber *h*, 60 at the end of which the carbon oxides pass out. The sulphur-vapors obtained in this way are condensed in *g* and *h* into the form of liquid sulphur, which is withdrawn through the pipe *o*.

65 We are well aware that sulphurous acid has before this been reduced to sulphur by conducting it through a glowing bed of fuel. In this process, however, a considerable expenditure of fuel is required for heating the gases 70 comparatively poor in SO_2 , which mostly consists of atmospheric nitrogen and oxygen. Further, the free oxygen contained in the gases causes a large portion of the reducing-fuel to be uselessly consumed; also, large quantities 75 of neutral gases are generated, which are an obstacle to the reduction of the sulphurous acid to sulphur, and also to the reduction of the separated finely-distributed sulphur. Finally, while one portion of the SO_2 molecules are quite 80 unaffected the other portion, on the contrary, is reduced to carburet of sulphur.

75 The reducing process in conducting the SO_2 through or over glowing fuel does not proceed precisely according to the formula $\text{SO}_2 + \text{C} = \text{CO}_2 + \text{S}$, but rather a gaseous mixture is obtained, which consists more or less of carbonic acid, carbonic oxide, sulphurous acid, sulphur-vapor, carburet of sulphur, and, under certain circumstances, hydrogen sulphide and 90 water-vapor. By the employment of a longer bed of fuel and by conducting the SO_2 more slowly through the same or over the same the contents in SO_2 would decrease; but, on the other hand, carburet of sulphur and the carbonic oxysulphide would increase in quantity. By the employment of a shorter bed of fuel and quicker through-passage the last-mentioned gases would be present in a lesser degree; but, on the other hand, the larger por- 95 100

tion of the sulphurous acid would remain unreduced; hence it is evident that SO_2 gases which have been conducted through or over glowing fuel must remain a further interval of time as a glowing heat and excluded from any further influence. For this reason we cause the gases to pass through a chamber containing glowing fire-bricks. By our process we obtain carbonic acid and sulphur only.

10 What we claim as our invention, and desire to secure by Letters Patent, is—

The process of obtaining sulphur from furnace or calcination or roasting or similar gases by passing them through water, then separating the sulphurous-acid gas absorbed from the

water solution in a gaseous form by the application of heat, conducting the gases thereby generated through or over a glowing bed of fuel, and then maintaining the same at a glowing heat in the absence of a reducing agent, 20 substantially as described and illustrated.

In testimony whereof we have signed this specification in the presence of two subscribing witnesses.

EMIL HÄNISCH.
MAX SCHROEDER.
